CLAIM

The ornamental design for a wireless charger, as shown and described.

DESCRIPTION

FIG. 1 is a top, front, left side perspective view of a wireless charger, showing my new design in a first configuration; FIG. 2 is a top, front, left side perspective view of the wireless charger, shown closed in a second configuration; FIG. 3 is a top, front, left side perspective view of the wireless charger, shown open in a third configuration; FIG. 4 is a front view of the wireless charger, shown in the first configuration; FIG. 5 is a rear view thereof; FIG. 6 is a left side view thereof; FIG. 7 is a right side view thereof; FIG. 8 is a top plan view thereof; FIG. 9 is a top, rear, left side perspective view thereof; and, FIG. 10 is another perspective view of the wireless charger. The broken lines depict portions of the wireless charger that form no part of the claimed design.
